ORAL SYRINGE

Samuel Gilbert, Los Angeles, Calif.
(16661 Ventura Blvd., Encino, Calif. 91316)

Filed Feb. 15, 1967, Ser. No. 5,833

Term of patent 14 years

(Cl. D24—1)

FIGURE 1 is a perspective view of the syringe showing my new design;

FIGURE 2 is a side elevational view of the syringe;

FIGURE 3 is a front end view of the syringe; and

FIGURE 4 is a rear end view thereof.

The dominant features of my design reside in the specific configuration of the frusto-conically shaped housing in combination with the dispensing nozzle as best illustrated in FIGURES 1 and 2 of the drawings.

I claim:

The ornamental design for an oral syringe, substantially as shown and described.
